Carbon Remover

UNITED STATES PATENT OFFICE.

LOUIS BUNDY, OF MEDFORD, OREGON.

CARBON-REMOVER.

1,125,003.

No Drawing.

Application filed May 1, 1914. Serial No. 835,733.

Patented Jan. 12, 1915.

To all whom it may concern:

Be it known that I, LOUIS BUNDY, a citizen of the United States, and a resident of Medford, in the county of Jackson and State of Oregon, have invented a new and Improved Carbon-Remover, of which the following is a full, clear, and exact description.

My invention relates to means for removing carbon deposited by the combustion of 10 the hydrocarbon gases within internal combustion engines.

The object thereof is to provide a simple, inexpensive and efficient carbon remover which is in liquid form so that the same can 15 be easily applied as a wash, by rubbing with it, or spraying the part covered with carbon under pressure or otherwise.

The ingredients forming the liquid carbon remover are potassium nitrate, 20 denatured alcohol, a trace of anilin for coloring and water; a sufficient quantity of the latter being added to make one gallon of the carbon remover. The proportions I prefer to use are substantially as follows: potassium nitrate, sixteen ounces; ninety-six fluid 25 ounces of water (approximately); about thirty-two fluid ounces of denatured alcohol; and a trace of anilin. The ingredients are preferably mixed in the following order:

Copies of this patent may be obtained for five cents each, by addressing the "Commissioner of Patents Washington, D. C."

The nitrate is dissolved in water and to this 30 solution the alcohol is added, then the same is colored with anilin.

The liquid mixture made as above described forms a perfect carbon remover which is quick in its action and which is not 35 injurious to the parts from which the carbon is to be removed.

My carbon remover is better applied by putting it into the air intake of the carbureter and allowing it to be drawn or sucked 40 in with the gas, thus simplifying the operation, as the same does away with the necessity of taking the engine apart.

Having thus described my invention, I claim as new and desire to secure by Letters 45 Patent:

A liquid carbon remover consisting of 66.6% of water, 11.2% of potassium nitrate, 22.2% of denatured alcohol, and a trace of 50 anilin.

In testimony whereof I have signed my name to this specification in the presence of two subscribing witnesses.

LOUIS BUNDY.
